UNITED STATES PATENT OFFICE.

AXEL G. GULBRANSEN, OF CHICAGO, ILLINOIS, ASSIGNOR TO GULBRANSEN-DICKINSON COMPANY, OF CHICAGO, ILLINOIS, A CORPORATION OF ILLINOIS.

ACTION-BRACKET.

1,385,076.

Specification of Letters Patent. Patented July 19, 1921.

Application filed October 15, 1917. Serial No. 196,588.

To all whom it may concern:

Be it known that I, AXEL G. GULBRANSEN, a citizen of the United States, residing at Chicago, in the county of Cook and State of Illinois, have invented a certain new and useful Improvement in Action-Brackets, of which the following is a full, clear, concise, and exact description, reference being had to the accompanying drawings, forming a part 10 of this specification.

My invention relates to action brackets for pneumatic player pianos. The bracket of my invention is intended to support both the piano action and the pneumatic player 15 action for operating the piano action. Heretofore, the customary practice has been to support these actions individually upon brackets and upon the body of the piano, the majority of these modes of support being 20 objectionable due to the difficulties of removal and adjustment of the actions and the likelihood of displacement of one action relative to the other due to warping of wood supports or frames.

The particular points of utility accruing to the use of my brackets are:

First—both actions are applicable and removable as a unit which makes them decidedly advantageous as a combined attachment for an ordinary piano;

Second—both actions are adjustable as a unit relative to the strings and keys; and

Third—the pneumatic action is independently adjustable and independently removable, relative to the piano action.

In the drawings:

Figure 1 is a side elevation of the bracket, with the piano and pneumatic actions mounted thereon; and

Fig. 2 is a front elevation of the same.

The bracket 10 made entirely of metal, is supported upon adjusting screws 11 and 12 in the key bed 13. I have illustrated but a single bracket, though of course it is to be understood that a bracket is employed at each end of the piano for supporting the ends of the piano and pneumatic actions. The adjusting screw 11 has its shank threaded into the key bed 13 and has a spherical 50 head 14 engaging a flared socket in the base portion 10^a of the bracket 10. The flared socket allows the bracket to tilt with respect

to the screw 11 when the bracket is adjusted. The adjusting screw 12 threads into a block 15, on the key bed 13 and has a conical tip 55 engaging in a screw hole 16 in the bracket base 10^a. At the upper end of the bracket 10 is the arm 10^b which has a slot 17, in which lies the action bolt 18, which threads into the piano plate 19.

I have illustrated somewhat diagrammatically the piano action 20, as it will be evident that the specific details thereof do not enter into my invention and that the bracket of my invention is applicable to a 65 great variety of slightly dissimilar actions. Adjacent the base portion 10^a of the bracket is mounted the action rail 21 to which are pivoted the stickers 22, through the medium of the tongues 23. The keys 24 having 70 the customary capstan screws, lie beneath the stickers 22 in suitable position for engaging the ends of the stickers. Intermediate the bracket 10 is another action rail 25 to which are pivoted the wippens 26, the 75 damper levers 27 and the hammer butts 28. The action rail 25 abuts the cheeks 29, protruding from the bracket 10, and is secured to the cheeks by the screws 30. A spring rail 31, for coöperation with the damper rods 80 32, is mounted on the upright arm 10^b, which is bulged outwardly at this particular point to provide sufficient body for receiving the screws 33. A ledge portion 10^c of the bracket 10 seats the cushion block 34 of the 85 hammer rail 35.

The operation and functions of these various elements of the piano action will be obvious to those skilled in the art and no description thereof will be made.

An adjusting screw 36 threads into the screw hole 16 and supports on its pointed end the lower edge of the channel board 37. A lock nut 38 locks the screw 36 in any adjusted position. An extending arm 10^d on 95 the bracket 10 has threaded therein a similar adjusting screw 39 and lock nut 40 which supports the upper edge of the channel board 37. Small metallic plates 41 screwed to the edges of the channel board, receive the screws 36 and 39 in conical holes therein, thereby preventing penetration of the channel board by the screws.

The pneumatic action 42 comprises the

stack of pneumatics 42', mounted on the rear face of the channel board 37, each pneumatic having an individual push rod 43, connected to the movable leaf of the pneumatic, and sliding through the guide strip 44. A head 45 on the push rod 43 engages a button 46 on its individual wippen 26 for oscillation of the wippen upon contraction of its associated pneumatic 42', in a manner which will be apparent to those skilled in the art.

From the foregoing it will be apparent that the piano action and the pneumatic action in their mountings upon the bracket, 15 comprise a unit applicable and adjustable as a unitary structure. To incline or raise or lower both actions, as for varying the proximity of the hammers 47 to the strings 48, or for adjusting the engagement between 20 the stickers 22 and the keys 24, it is only necessary to manipulate the action bolt 18 and the adjusting screws 11 and 12. These constitute the three points of support of the bracket, are readily applicable to the ordinary piano, and render the combination universal as an adapter or attachment. By unscrewing the action bolt 18, the actions and brackets may be removed as an entirety, thus 25 facilitating adjustment and repair.

30 The pneumatic action can be independently adjusted as for securing the proper engagement between the push rod heads 45 and the wippen buttons 46, by manipulation of the adjusting screws 36 and 39. These 35 screws also permit facile removal of the entire pneumatic action from the bracket. The rubber tubes between the tracker bar and action channel bracket (not shown) are the only exterior connections of the pneumatic 40 action and these may be readily removed.

I do not intend to be limited to the precise form of the bracket illustrated nor to the specific means of adjustment, except as set forth in the appended claims.

45 I claim:

1. In a player piano, the combination of a bracket, said bracket being formed with a vertical body portion and two lateral members extending from said body portion, said 50 body portion adapted to support a piano action, said lateral members adapted to support a pneumatic action positioned therebetween, adjustment means coöperating with said bracket to adjust the position of the latter independently of the adjustment means of the pneumatic action and adjustment means coöperating with said pneumatic action to adjust the pneumatic action relative to the piano action.

60 2. In a player piano, a bracket, said bracket comprising a rear upright portion and two lateral portions extending forwardly therefrom, said upright portion adapted to support a piano action and said 65 lateral portions adapted to support a pneu-

matic action directly between them, said bracket having means for adjusting the pneumatic action independently of the piano action.

3. In a player piano having a plurality 70 of strings and a plurality of keys, a supporting bracket, a piano action mounted on said bracket, said bracket having a pair of integral arms projecting therefrom, a pneumatic action mounted on said arms, means 75 on said bracket for adjusting the position of said piano action relative to said strings and keys, and means on said arms for adjusting the position of said pneumatic action relative to said piano action. 80

4. In a player piano, a key bed, adjusting screws in said key bed, a bracket supported on said adjusting screws, a plurality of rails mounted on said bracket, a piano action supported on said rails, a pair of vertical adjusting screws one above the other in said bracket, and a pneumatic action supported on and between said latter adjusting screws. 85

5. In a player piano having a frame and a key bed, a bracket comprising a substantially vertical portion having suitable means for supporting a piano action, and a pair of laterally extending arms, an adjusting screw for the lower end of said vertical portion supported by the key bed, a second adjusting screw for the vertical portion supported on the piano frame, and a third adjusting screw for supporting one of said laterally extending arms upon the key bed, said laterally extending arms supporting a pneumatic channel board between them. 90

6. In a player piano having a frame and a key bed, a bracket comprising a substantially vertical portion having suitable means for supporting a piano action, and a pair of laterally extending arms, an adjusting screw for the lower end of said vertical portion supported by the key bed, an adjustable action bolt for the vertical portion supported on the piano frame, and a second adjusting screw for supporting one of said laterally extending arms upon the key bed, said laterally extending arms supporting a pneumatic channel board between them, and adjusting screws in the outer ends of said laterally extending arms for adjusting the channel board on said arms independently of the adjustment of the bracket as a whole. 110

7. In a player piano, a key bed, adjusting screws in said key bed, a bracket supported 120 on said adjusting screws, a plurality of rails mounted on said bracket, a piano action supported on said rails, a pneumatic channel board, a pair of adjustable supporting screws mounted on said bracket, one 125 above the other, said screws engaging the channel board on its upper and its lower sides respectively, and a pneumatic action supported on the channel board and adapted to operate the piano action. 130

8. In a player piano, a key bed, adjusting screws in said key bed, a bracket supported on said adjusting screws, a plurality of rails mounted on said bracket, a piano action supported on said rails, a pair of adjusting screws arranged in said bracket one above the other in approximate axial aline-

ment, and a pneumatic action engaged directly and supported between said screws.

In witness whereof, I hereunto subscribe my name this 13th day of October A. D. 1917.

AXEL G. GULBRANSEN.
